UNITED STATES PATENT OFFICE.

ELMER HIATT, OF MILFORD, CONNECTICUT.

CLOTH-SURFACING DEVICE.

Application filed November 10, 1924. Serial No. 749,020.

To all whom it may concern:

Be it known that I, ELMER HIATT, a citizen of the United States, residing at Milford, in the county of New Haven and State 5 of Connecticut, have invented certain new and useful Improvements in a Cloth-Surfacing Device, of which the following is a specification.

This invention relates to cloth surfacing 10 devices.

The primary object of this invention is the provision of an improved device adapted to be manually used in order to more effectively bring out the nap on cloth and 15 garments.

A further object of this invention is the provision of an improved cloth surfacing device, of a simple and compact nature, which may be used to effectively raise and 20 re-adjust the nap on shiny surfaces of garments or cloth.

A further object of this invention is the provision of a cloth surfacing device, preferably in the form of a brush, with a novel- 25 ly constructed brush head, and improved means for mounting the same so that it may most effectively perform its function in picking up the nap of garments.

Other objects and advantages of this in- 30 vention will be apparent during the course of the following detailed description.

In the drawing, wherein for the purpose of illustration is shown only a preferred embodiment of this invention.

Figure 1 is a plan view of the improved cloth surfacing device.

Figure 2 is a side elevation of the im- 35 proved device.

Figure 3 is a longitudinal cross sectional view taken through the improved device, substantially on the line 3—3 of Figure 1.

Figure 4 is an enlarged fragmentary view of the brush head and brush head mounting portion of the device.

Figure 5 is a cross sectional view taken through the handle structure of the improved device substantially on the line 5—5 of Figure 3, and

Figure 6 shows a modified detail of the 50 invention.

In the drawing, wherein similar reference characters designate corresponding parts throughout the several views, the letter A may generally designate the improved 55 device, which may consist of a brush head structure B; frame C; and handle piece D,

The brush head B is of novel construction, preferably including a shaft 10, formed of a pair of twisted wires 11 and 12, which are evenly twisted to clamp wire 60 napping strands 13 therebetween, preferably intermediate the ends of the wires 13, in order to provide a substantially cylindrical shaped brush head; the shaft of which is of relatively small diameter, with relatively long radially extending napping wires, flexible in nature, although sufficiently rigid to not flex too easily, in order that the nap of a garment may be "picked up", so to speak. The wire strands 13 are 65 70 preferably brass wire strands, and the outer surfaces thereof terminate at the periphery of the brush head. It is to be noted from Figure 4 of the drawing, that the terminal portions 15 of the shaft 10 are free of 75 the wire strands, and provide spindles or bearing extensions, so to speak, which may be utilized to support the brush head in the frame C. The twisted wires 11 and 12 are of such nature that they will not 80 bend transversely, so that the alignment of the shaft 10 is always preserved. At each of the extensions 15, it is to be noted that the shaft wires are rather sharp, in order to assist in fixedly supporting the hubs 85 17. The hubs 17 each consists of the hollow cylindrical body portion 18, providing a pocket 19 which receives an end 15 of the shaft, and it also consists of an outwardly extending flange 20, which is adapt- 90 ed to cooperate in receiving a movable washer 21 thereagainst, whereby to maintain the wire bristles of the brush head B in position, against lateral bending.

The frame C of the improved brush A 95 is preferably of one piece of material, and at the ends thereof is bent to provide brush head supporting arms 23 and 24, which at their rear ends are bent in right angled relation, to provide the inturned aligning 100 portions 25 and 26 respectively. The frame C furthermore includes the substantially parallel portions 27 and 28, extending preferably in right angled relation integral with the portions 25 and 26, and which 105 portions 27 and 28 are connected by a bight 30, and preferably between the bight 30 and the portions 25 and 26, the portions 27 and 28 are outwardly bowed, as at 31, to receive the handle piece D therebetween, as will be 110 subsequently mentioned. The frame C is thus formed of a single piece of metal strip

material, and the portions 27 and 28 may alone be used as the handle for the brush A, or they may be used as a means for attaching a hand grasping piece D therebetween.

As is shown in the drawing the brush head supporting arms 23 and 24 of the frame C at their outer ends are provided with openings 33 therethrough, which detachably receive the body portions 18 of the hubs 17 therein; the arms 23 and 24 of the frame being of necessity flexed outwardly so that the same as sprung frictionally clamp the brush head B therebetween, with the inside surfaces of the arms 23 and 24 resting against the flanges 20 of the hubs 17, in a friction retarding relation. This spring action of the arms 23 and 24 tends all the more to force the hubs 17 into a fixed relation with the pointed ends 15 of the shaft 10, so that the hubs 17 are fixed with the shaft, and said hubs rotate in the openings of the arms 23 and 24.

Means for adjusting the clamping spring action which the frame C will have on the brush head B is provided, and consists of a bolt member 35, which extends transversely through aligning openings in the frame arms 27 and 28, adjacent the inwardly extending portions 25 and 26; the head 36 of this bolt 35 engaging the arm 27, and the screw threaded shank of said bolt 35 extending through the opening of the arm 28, to receive a thumb nut 37, by means of which the frame arms 27 and 28 may be adjusted with respect to each other, to increase the resilient clamping action of the arms 23 and 24 on the brush head B, and as can readily be understood. This clamping action of the frame C on the brush head B is important, since it is preferred that the brush head B rotate in the frame arms 23 and 24, only when considerable pressure is brought to bear by rolling the brush head B along the goods whose nap is to be freshened.

The handle D may be of any approved material, such as hard rubber, pyroxyline, bone, ivory, or the like, and it includes the main body portion 40, of substantially oval shaped formation, preferably grooved at 41 to receive the frame arms 27 and 28 and the bight portion 30 therein. The body portion 41 forwardly thereof includes the slot 43, which is adapted to receive therein the transverse shank portion of the bolt 35, between the frame arms 27 and 28. In lieu of this slot 43 merely a transverse opening may be provided, although the slot 43 is the most convenient means of manufacturing the handle piece D, in order to permit facile assemblage thereof on the frame C.

The use of the improved napping brush A will be apparent to anyone skilled in the art to which this invention relates. It is merely necessary to grasp the handle of the

improved brush, and by reciprocating the same over a piece of goods, with the ends of the brush bristles in engagement with the nap of the garment, sufficient roll action is given the brush head B to permit the easy operation of the device, and yet sufficient retarding or brake action is placed on the brush head B by the spring action of the frame C thereon, in order to insure that the ends of the brush head wire bristles 13 will "pick up" the nap of the garment, and produce substantially the original effect. The washer members 21 may also appropriately be termed guards, for the reason that the peripheral edges thereof are formed on a diameter which is just slightly less than the diameter of the brush head B, so that the ends of the bristles 13 extend slightly outwardly of the periphery of the guard washers 21, just a sufficient distance to insure that they will have the required penetrating effect in the nap of the garment, without damaging the same. It is to be noted, as is illustrated in Figures 1 and 4, that the circumferences of the brush head B, at the ends thereof, is slightly reduced, as shown at 45 in Figure 4 of the drawing; the circumference of the brush head B being formed on a slightly reducing diameter, as it approaches the guard washers 21. Incident to the provision of the relatively small diametered shaft 10, and the long bristles 13, the brush head B is of particular value in connection with the purpose which it is to serve, since the bristles of the brush will have the required flexibility in order to raise the nap of the garment.

In Figure 6 of the drawing is illustrated a modified detail of the invention, which is one-piece, and adapted to replace the hubs 17 and the flanges 21 of the structure above described. This detail 50 consists of the hollow cylindrical hub portion 51, provided with a pocket 52 to receive the ends 15 of the shaft 10 therein, and provides the relatively large diametered laterally extending guard flange 53 of the same diameter as the washers 21 above mentioned, so that the outer periphery 54 thereof is disposed in cooperating relation with respect to the periphery of the brush head B, in order to permit the proper penetration of the garment as the brush rolls, and to permit the bristles 13 to flex properly, without liability of bending thereof when too great a pressure is brought to bear on the brush. Incident to the provision of the long bristles 13 unless the guard flanges provided by the washer 21 or flanges 53 were provided, these bristles would be apt to be distorted when any undue pressure is brought to bear in operating the brush.

The means for adjusting the tensioning of the frame C to produce the proper retarding action on the brush head B is apparent from the foregoing description. With this ten-

sioning device it is sometimes conceivable that the spring arms 23 and 24 will act with too great force lengthwise of the shaft 10. With a rigid one-piece shaft of small diameter this force would tend to bend the shaft between its ends and consequently destroy the circumferential alignment of the brush head. However, by making the shaft 10 of twisted wires 11 and 12, it will flex somewhat longitudinally of the shaft, without loosening the bristles, and in this way any excessive force of the tensioning adjustment provided by the frame C will be taken care of, without destruction to any parts of the brush.

Various changes in the shape, size, and arrangement of parts may be made to the form of invention herein shown and described, without departing from the spirit 20 of this invention or the scope of the claims.

I claim:

1. In a cloth surfacing device the combination of a brush head including a shaft, a frame including yieldable brush head supporting arms provided with openings at their outer ends, a hub member for each end of the brush shaft providing a socket open at one end and closed by an end wall at the opposite end, and against which closed end 25 wall the end of the shaft of the brush head abuts to limit the inward movement of the hub members on said shaft, said hub members being adapted to bear in the openings of said arms of the frame and including means 30 to hold them in place against displacement.

2. In a cloth surfacing device the combination of a brush head including a small 35 diametered shaft formed of twisted wires with bristles clamped therebetween, a frame 40 rotatably supporting said shaft, and means for retarding movement of the shaft therein.

3. In a cloth surfacing device the combination of a brush head including a shaft 45 formed of twisted wires and bristles clamped between said wires of the shaft, said shaft at its ends providing portions free of bristles, a frame providing yieldable supporting arms, and means mounting the ends 50 of said shaft in said yieldable supporting arms so that said yieldable supporting arms act with a braking action on said brush head tending to retard movement thereof with respect to the frame.

55 4. In a cloth surfacing device of the class described the combination of a brush head including a shaft and bristles suitable for picking up the nap of worn garments, and a frame including yieldable arms supporting said shaft so as to place a braking action on the brush head normally retarding the revolution of the same with respect to the frame.

60 5. In a cloth surfacing device of the class described the combination of a brush head 65 including a shaft formed of twisted wires

and bristles supported by the twisted wires of a nature suitable for picking up the nap on worn garments, said shaft at its ends being free of bristles, substantially cylindrical shaped hub members carried at the ends of said shaft, and a frame including yieldable arms receiving the hubs therein whereby to assert a braking action on the brush head tending to normally retard revolution of the same with respect to the frame. 70

6. As an article of manufacture a brush head suitable for cloth surfacing including a small diametered shaft, relatively long wire bristles supported by the shaft and being of lengths several times greater than the diameter of said shaft, a frame and means mounting the shaft in the frame to place a braking action on the brush head. 75

7. In a cloth surfacing device the combination of a brush head including a shaft carrying stiff bristles of a nature adapted to pick up the nap of cloth, a frame including a pair of yieldable and resilient supporting arms provided with openings at their free ends, hub members including cylindrical bodies adapted to bear in the openings at the ends of the arms of said frame, said cylindrical bodies of the hub members providing pockets open at one end and closed at the opposite end for receiving the ends of the shaft of the brush head therein, said hub members furthermore including outwardly extending flanges at the open ends of said pocket adapted to engage at the inside surfaces of the arms of said frame, and means for flexing said arms so that they exert an inward pressing action on the hub members and against the ends of the brush head shaft to normally tend to retard the rotational movement of the brush head upon said frame. 85

8. In a brush of the class described the combination of a brush head including a relatively small diametered shaft of twisted wire and radially extending flexible wire bristles, hub members carried at the ends of said shaft, guard flanges carried by said shaft to prevent unnecessary bending of the bristles of the brush, and a frame receiving said hubs in bearing relation therein. 90

9. In a brush of the class described the combination of a brush head including a relatively small diametered shaft of twisted wires and radially extending flexible wire bristles, hub members carried at the ends of said shaft, guard flanges carried by said shaft to prevent unnecessary bending of the bristles of the brush, a spring frame receiving said hubs in bearing relation therein, and means for adjusting the spring action of the frame on the brush head to retard rotation thereof with respect to the frame. 105

10. In a cloth surfacing device the combination of a brush head, a frame including yieldable arms, and means for adjusting the 110

yieldable action of the arms to assert a braking action on said brush head.

11. In a cloth surfacing device the combination of a brush head, a frame including 5 yieldable arms, means for adjusting the yieldable action of the arms to assert a braking action on said brush head, and handle means carried by said frame.

12. In a cloth surfacing device the combination of a frame including spaced forwardly supporting arms and spaced rearwardly extending arms, a brush head rotatably carried by said forwardly extending arms, and a hand grasping piece detachably 15 carried by said rearwardly extending arms.

13. In a cloth surfacing device the combination of a brush head, a metal frame including a substantially U-shaped handle portion consisting of spaced arms and laterally extending resilient brush head supporting arms, and tensioning means acting on 20 said first mentioned arms whereby the sup-

porting arms may be sprung to act with a braking action on the brush head.

14. In a cloth surfacing device of the class 25 described a brush head, and a one piece metal frame bent intermediate its ends to provide handle supporting arms in spaced relation which at their outer ends are provided with laterally extending portions, 30 said laterally extending portions at their outer ends being provided with forwardly extending brush head supporting arms, means extending transversely between said handle supporting arms for adjusting the 35 clamping action of the brush head supporting arms with respect to the brush head, and a handle member peripherally grooved to receive the handle supporting arms of the frame therein and at its forward end being provided with a transverse opening to 40 receive said adjusting means.

ELMER HIATT.
